DESIGN FOR A FLASHLIGHT CASING

Burdon P. Hyde, Naugatuck, Conn., assignor to
Scovill Manufacturing Company, Waterbury,
Conn., a corporation of Connecticut

Application October 21, 1936, Serial No. 65,414

Term of patent 14 years

To all whom it may concern:

Be it known that I, Burdon P. Hyde, a citizen of the United States of America, residing at Naugatuck, in the county of New Haven and State of Connecticut, have invented a new, original, and ornamental Design for Flashlight Casings, of which the following is a specification: reference being had to the accompanying drawing, forming a part thereof.

Fig. 1 is a side view of a flashlight casing, embodying my new design.

Fig. 2 is a front end view of the same.

Fig. 3 is a rear end view of the same.

I claim:

The ornamental design for a flashlight casing, substantially as shown.

BURDON P. HYDE.
